MASSAGING AND STRETCHING MACHINE

Robert P. Fisher, Los Angeles, and John P.
Geiger, Montrose, Calif.

Application January 10, 1948, Serial No. 1,587

1 Claim. (Cl. 128—71)

1

This invention relates to massaging and stretching machines, and more particularly to a machine or table upon which the human body can lie and which can be power operated for the purpose of massaging the back and spine, and which can at the same time be connected to the feet and to the head for intermittently applying a stretching action and treatment to the body.

Among the salient objects of the invention are: to provide a machine or table of the character referred to which is simple, practical and economical and which has certain adjustments to adapt it to varying intensity both in the massaging action and in the stretching action applied to the body; to provide a machine in the form of a table with the operating members and elements on the top thereof and through the top thereof, and with the power and operating mechanism enclosed therein, under the top.

In order to explain our invention, we have shown on the accompanying sheet of drawings one practical embodiment thereof which we will now describe:

Figure 1 is a longitudinal sectional view through a massaging and stretching table embodying our invention, with a human body indicated thereon in light broken lines;

Figures 2 to 6 inclusive, are sectional views taken, respectively, on the lines 2—2, 3—3, 4—4, 5—5 and 6—6, on Fig. 1.

Referring now in detail to the drawings, the table structure of our invention can be of any desired type or size and of any ornamentation or streamlined design. For the purposes of this application, we have shown a simple table top 7, with supporting sides and ends, 8, 8, and 9, 9 and base 10, somewhat in the form of a box or cabinet, with a slot-like opening 11 in the top 7, extending lengthwise thereof, as seen in Figs. 1 and 3.

Suspended under said opening 11, by brackets 12, 12, at each end are two channel members, as 13, 13, open toward each other, as seen in Fig. 3, and mounted to run back and forth in and between these channel members is a carrier member 14, having wheels, as 15, 15, to run in said channels, as seen in Figs. 1 and 3.

Secured to the under side of this carrier member 14 is a tubular member 16, interiorly threaded and provided with handles 17, 17, for turning it in its support 18. Operating through said carrier member 14 and through said tubular member 16 is a rack 19, having a channel 20 in one side, to receive a tongue 21 on said carrier member 14 to prevent said rack from turning, while allowing it to be moved up and down by turning said

2

tubular member 16, in a manner which will be understood from the showing in Fig. 1.

On the upper end of said rack, is a supporting Y, designated 22, and in which is supported a massaging wheel or roller 23 having in the present showing two soft flexible members, as 24, 24, which is shown to operate up through said opening in the table top, and which can be adjusted up and down as may be desired by means of the tubular member 16.

Mounted on the base 10, within said cabinet is a motor 25, whose drive shaft is connected with a gear reduction case 26, having a crank 27 on the outer side thereof, connected by means of a link 28, with the lower end of a lever 29, pivotally supported on a rigid bracket 30 secured in the corner of said cabinet, as shown.

The upper end of said lever 29 has a link 31 connected therewith and extended to and connected with the upper end of a lever 32, pivotally supported at 32' on a frame member 33.

The lower end of said lever 32 is adjustably connected with the lower end of the lever 32, as at 34, and is secured in place of adjustment by a set screw 35. The opposite end of said member 34 has pivotally connected with it, as at 36, a curved operating rod or member 37, the opposite end of which is adjustably connected in a bracket 38, on the underside of the end of said carrier member 14, as illustrated at 39, with a set screw 40 for securing said connection. Through this connection said carrier member and massaging wheel are moved back and forth by the motor, according to the adjustment on the lever 32 of the operating member 37.

Also connected with the upper end of the lever 29, is a second link, as 41, the end of which is connected to an angle member 42, on which is secured a tubular member 43, extending out through the end wall of the cabinet, as shown at 43'. Operating in said tubular member 43 is a telescoping member 44, the outer end of which is connected with a depending finger 45, from a cross bar 46, the opposite ends of which carry two channel members or blocks, as 47, 47, with clamp plates, as 48, 48, therein and with set screws 49, 49, for tightening said clamp plates 48, 48, on the two ends of said two straps, as 50, 50, shown in section therein.

The inner end of the telescoping member 44 is forked to straddle the end of the angle member 42, as seen in section in Fig. 2, and as indicated in light broken lines in Fig. 1. This telescoping member is not secured to the angle member 42, but is free when said angle member 42

is moved to the right to follow by relaxation of the body of the patient, but when said angle member is moved to the left, it pushes said telescoping member 44 and its connection through the parts 45, 46 and 47 to put tension on the straps 50.

Each of said straps 50 is bifurcated at its end, as at 51, and has secured thereto an ankle strap, as 52, adapted to be secured around the ankle of the person receiving the treatment, as indicated in Figs. 1 and 3, by lacing. Through these ankle straps, as shown, stretching is intermittently applied to the limbs of the patient, as will be understood from the foregoing description.

Mounted on the head end of the table top 7, is a neck rest or member 53, held on a plate 54, having an upstanding flange or rib 55 interfitting with said neck rest, and having its opposite sides turned under the opposite edges of the table top 7, as seen in Fig. 4.

Also mounted on said plate 54 is a head band or arch member 56, having its opposite ends extended under holding brackets 57, 58, with screws 58, 59, for holding them in place. On the rearward end of said plate 54, at opposite sides, are two upstanding brackets 59, 59, on which are two straps, as 60, extended rearwardly and anchored to the opposite ends of a T-member 61, similar to that shown in Fig. 5, the stem portion of which is connected with a piston rod 62, as at 63, the piston of which operates in a cylinder 64, adjustably supported in a bracket 65, and provided on its under side with teeth 64', to mesh with a gear 66, on a shaft 67, held in a bracket 68 and the side wall 8 of the cabinet, as at 69, Fig. 4, which also shows a lock nut 70 on said shaft 67, and an operating head 71, said cylinder having a pressure tube 72 connecter therewith and connected with a pressure guage 73, on the side of the cabinet, as shown.

Thus we have provided a table mechanism on which the human body can lie and which mecha-

nism can be power operated, with suitable adjustments, to massage the spinal column and at the same time intermittently apply a stretching and relaxing treatment to the head and feet in the manner indicated, and while we have shown certain details of arrangement for illustrative purposes, we do not limit ourselves to these details, knowing that many changes can be made therein without departing from the spirit of our invention, and we do not, therefore, limit our invention to the showing made except as we may be limited by the hereto appended claim.

We claim:

1. In a massaging and stretching machine, a table structure having an opening therethrough, a massaging element operable up through said opening to engage the body of a person lying on said table, said element being adjustable vertically, a motor, operating connections from said motor to said massaging element for oscillating it back and forth, means for attachment to the feet of said person, said means being operatively connected with the motor for intermittently pulling on said feet, means for attachment to the head of said person for applying pull in the opposite direction from that applied to the feet, a cylinder with piston operable therein and connected with said head pulling means, and a guage connected with said cylinder for indicating the pressure being applied to said stretching means.
